INVENTOR:

Albert N. Norris

UNITED STATES PATENT OFFICE.

ALBERT N. NORRIS, OF RUSHVILLE, INDIANA.

CORN-PLANTER.

SPECIFICATION forming part of Letters Patent No. 276,869, dated May 1, 1883.

Application filed November 3, 1882. (No model.)

To all whom it may concern:

Be it known that I, ALBERT N. NORRIS, a resident of Rushville, in the county of Rush and State of Indiana, have invented a new 5 and useful Improvement in Corn-Planters, of which the following is a specification, having reference to the accompanying drawings.

My invention relates to that class of corn-planters in which the amount of seed delivered is regulated by a bevel-wheel attached to the feed-plate and provided with two or more concentric rows of cogs, and a pinion on the driving-shaft adapted to slide thereon and to intermesh with either row of cogs on the first-mentioned wheel.

In this class of corn-planters as heretofore constructed the means for throwing the pinion out of gear with the bevel-wheel attached to the feed-plate and the means for moving 20 said pinion from one row of cogs to another on the bevel-wheel have been separate devices.

The object of my invention is to provide a more convenient means for changing the pinion from one row of cogs to another on the 25 feed-wheel; and it consists, first, in mounting the pinion in a bearing having a combined swinging and sliding motion, as hereinafter fully described.

My invention consists, further, in the combination, with the above-mentioned pinion and its swinging sliding bearing, of a lever, a swinging fulcrum therefor, a notched segment-bar, and means for securing the lever in the notches of the segment-bar, whereby the pinion is moved and controlled, as hereinafter 35 fully set forth.

The accompanying drawings illustrate my invention, in which Figure 1 is a side elevation of my invention, the seed-box, feed-plate, 40 and shaft and its bevel-gear being shown in section. Fig. 2 is a rear elevation of the same.

Like letters refer to the same parts in both figures.

a represents the rear end of the corn-planter frame; *b*, the seed-box, and *c* the feed-plate. Secured to the feed-plate shaft is a bevel-wheel, *e*, having three concentric rows 45 of teeth.

f is a pinion having teeth adapted to intermesh with either row of teeth on wheel *e*, and

is provided with a cylindrical sleeve, *g*, which has a bearing in the sliding arm *h*. The sleeve *g* has a central longitudinal square hole, in which the squared end of the driving-shaft *i* loosely fits. Shaft *i* is supported at its other 55 end by a suitable socket-bearing, and is caused to revolve by a pair of bevel-wheels connecting it with the carrying-wheel in the usual well-known manner. Arm *h* is fastened to or formed upon a rod, *j*, which is adapted to slide 60 and partially revolve in a bearing, *k*, secured to the frame *a*.

To the rear end of rod *j* is pivoted one end of a lever, *l*, which has its fulcrum at *m* on the swinging standard *n*, the lower end of 65 standard *n* being pivoted in bearings *o o*, secured to the frame. Lever *l* is provided with a projecting rib, *p*, Fig. 2, which is adapted to engage either one of a series of notches, *t*, in a bracket or segment-bar, *r*, secured to the 70 frame. Lever *l* is held in place against bar *r* by means of a thumb-latch, *S*, pivoted to one side of the lever in such manner as to embrace the bar.

The operation of my device is as follows: 75 The operator, desiring to change the amount of corn dropped during one revolution of the carrying-wheel, seizes lever *l* and disengages it from the segment-bar, and by pressing his thumb on latch *S* swings the lever away from the bar, 80 thus withdrawing rib *p* from the notch *t* and partially revolving rod *j* and arm *h*, thereby dropping pinion *f* out of contact with bevel-wheel *e*. By pressing the lever backward or forward, rod *j* and carrying-arm *h* are slid correspondingly till pinion *f* is brought opposite another row of teeth on wheel *e*, with which it is engaged by swinging the lever back against the segment-bar and dropping latch *S*, rib *p* engaging another notch and preventing the slipping of the pinion backward or forward. Pinion *f* is now revolved by the forward movement of the planter through shaft *i*. 90

I claim as my invention—

1. In a corn-planter, the combination, with 95 a feed-wheel having two or more concentric rows of cogs, a driving-shaft, and a pinion adapted to slide longitudinally thereon, and to engage either of the rows of cogs on the feed-wheel, of a bearing for said pinion adapt- 100

ed to have a combined sliding and swinging movement, as shown and described, for the purpose specified.

2. In a corn-planter, the combination, with a feed-wheel having two or more concentric rows of cogs, a pinion, and a bearing therefor having a combined swinging and sliding movement, of a lever pivoted to said bearing, a swinging fulcrum for said lever, a notched

segment-bar, and means for securing the lever in the notches of the segment-bar, all substantially as shown and described, for the purpose specified. ¹⁰

ALBERT N. NORRIS.
